204,127

POWER OPERATED ROTARY TOOTHBRUSH

David J. Syvertson, 5921 W. 88th St.,
Shawnee Mission, Kans.

Filed Sept. 29, 1965, Ser. No. 87,216

Term of patent 14 years

(Cl. D9—2)

Fig. 3

Fig. 5

Fig. 4

FIGURE 1 is a top view of a power operated rotary toothbrush embodying my design;

FIGURE 2 is a side view thereof;

FIGURE 3 is a bottom view thereof;

FIGURE 4 is a view of one end along the line 4—4 of FIGURE 1; and

FIGURE 5 is a view of the end opposite that shown in FIGURE 4, along the line 5—5 of FIGURE 1.

I claim:

The ornamental design for a power operated rotary toothbrush, as shown.
